CLAIM

The ornamental design for a wristwatch, as shown and described.

DESCRIPTION

FIG. 1 is a front view of my new, original and ornamental design for a wristwatch;

FIG. 2 is a rear view thereof;

FIG. 3 is a right side view thereof;

FIG. 4 is a left side view thereof;

FIG. 5 is a bottom view thereof;

FIG. 6 is a top view thereof;

FIG. 7 is a right front perspective view thereof; and,

FIG. 8 is a rear and right side perspective view thereof.

The broken lines in the drawings are used to show portions of the wristwatch that do not form part of the claimed design.
